WHEEL RERAILER

James Bliss Haskell, Huntington, W. Va., assignor
to West Virginia Steel and Manufacturing
Company, Huntington, W. Va., a corporation
of West Virginia

Application August 1, 1949, Serial No. 107,965

9 Claims. (Cl. 246—423)

1

The invention relates generally to railway trackage and appurtenances therefor and primarily seeks to provide novel wheel rerailing means placeable opposite switch joints and adapted for quickly and positively effecting the rerailing of wheels which have been derailed.

It not infrequently happens that wheels of cars traveling over railway switches will become derailed, and it is quite a problem to get such wheels back onto the tracks, especially when it is attempted to do so without special equipment and without damaging the rails and the anchoring means therefor. Attempts have been made to devise rerailing means placeable opposite switch joints for the purpose stated, but such means have not been entirely satisfactory because of faulty design. They have been in a measure effective in guiding the wheels back onto the tracks as the trucks were drawn along thereover, but because of the inclusion of laterally sloping camming surfaces intended to support the wheels and simultaneously force them laterally as they were being drawn along, such devices have unnecessarily imposed great lateral strains on the trackage and its mountings. It is the purpose of the present invention to provide rerailer devices which are effective to bring about the desired rerailing of wheels positively and with facility while avoiding the problem referred to.

An object of the invention is to provide novel wheel rerailing devices of the character stated wherein are included upwardly inclined portions for lifting the wheels to a sufficient height for proper replacement on the rails, and flat horizontal portions for receiving the wheels from said inclined portions and over which the wheels may move during the actual rerailing process without imposing objectionable lateral strains on the rails or their mountings.

Another object of the invention is to provide a rerailer of the character stated wherein the upwardly inclined portion also is flat and horizontal in cross section so as to avoid any tendency to cam a wheel laterally as it is being drawn along over said inclined portion onto the flat and horizontal top portion.

Another object of the invention is to provide a rerailer of the character stated wherein there is included on the horizontal and flat top portion an upstanding camming rib bearing angular relation to a rail onto which a wheel being drawn over the rerailer is to be returned and effective to cam the wheel laterally over the horizontal and flat top surface onto said rail.

2

Another object of the invention is to provide a rerailer of the character stated wherein there is included an upright side wall disposed to oppose one rail and having recesses therein passing down through the bottom edge thereof in position for engaging over bolts forming part of the switch point securing means and constituting the sole means for holding the rerailer against endwise displacement.

10 With the above and other objects in view that will hereinafter appear, the nature of the invention will be more clearly understood by reference to the following detailed description, the appended claims and the several views illustrated in the accompanying drawings.

Figure 1 is a plan view illustrating a rail turnout with the invention applied thereon.

Figure 2 is a somewhat diagrammatic vertical cross section illustrating the process of rerailing a pair of wheels, the partially rerailed condition being shown in full lines, and the fully rerailed condition being illustrated in dotted lines.

Figure 3 is a plan view of the rerailer member designed to lie between the outside or straight stock rail and the converging curved closure rail.

Figure 4 is a side elevation of the member shown in Figure 3, looking at the side which opposes the curved closure rail and overlaps the juncture thereof at the respective switch point.

30 Figures 5 and 6 illustrate, in left and right end elevations, respectively, the rerailer member shown in Figure 4.

Figure 7 is an enlarged detail horizontal section illustrating the mounting of the rerailer member shown in Figures 3 through 6.

Figure 8 is a detail vertical cross section taken on the line 8—8 on Figure 7.

Figure 9 is a view similar to Figure 7 illustrating the mounting of the other rerailer member.

40 Figure 10 is a detail vertical cross section taken on the line 10—10 on Figure 9.

Figure 11 is a plan view of the rerailer member designed to lie between the straight closure rail and the converging inside or curved stock rail.

45 Figures 12 and 13 illustrate, in left and right end elevation, respectively, the rerailer member shown in Figures 11 and 9.

Figure 14 is a side elevation of the rerailer member shown in Figure 11.

50 In the example of embodiment herein disclosed, the invention is illustrated as applied on a conventional form of turnout including an outer or straight stock rail 5, an inner or curved stock rail 6, and a straight switch comprising

inner and outer straight switch points designated 1 and 8 respectively.

The turnout also includes a frog 9, a curved closure rail 10 connecting at one end with one frog rail section, and at its other end with the switch rail 8, and a straight closure rail 11 connecting at one end with the other frog rail section and at its other end with the remaining switch rail 7. Continuation rails 12 and 13 also connect with the frog in the manner illustrated.

The various rails are supported on suitably arranged ties 14, being removably secured thereon by suitable securing devices 15, and the frog 9 may be formed on a plate 16 which is suitably secured upon tie means in the manner clearly illustrated.

The switch points 7 and 8 are swingably mounted in the usual manner at 17 at the end of the respective closure rails 10 and 11, and said points are connected at their free ends as at 18. The connected ends of the switch points are connected by a thrust link 19 with the usual swingably mounted switch lever 20 which can be manipulated to place the switch point in position for causing a turn, or to a position in which the switch point 7 will engage the inner or curved stock rail 6 and cause said car or cars to proceed along the straight-way.

The previously described trackway structure, in itself, forms no part of the present invention and is shown and described merely to illustrate the location and manner of mounting and use of the rerailer structures embodying the invention and the conveyance of said rerailer structures with said trackway structures.

It will be apparent by reference to Figure 1 that the rerailer devices generally designated 21 and 22 are generally wedge shaped or tapered in plan view and are respectively fitted between the converging portions of the outside or straight stock rail 5 and the curved closure rail 10 between the converging portions of the straight closure rail 11 and the inside or curved stock rail 6. Each said rerailer lies opposite or straddles the respective switch point juncture with the closure rail 10 or 11.

The rerailer member 21 is shown in detail in Figures 3 through 8 and includes an outer upright wall 23 and an inner upright wall 24, said walls converging toward a transverse upright end closure wall 25 and being connected by a top 26 which is horizontal and flat in transverse cross section between the points 27 and 28. The top slopes downwardly and endwise slightly as at 29 toward the end closure wall 25, and slopes endwise and downwardly in a more marked degree as at 30 from the point 28 to the end extremity of the rerailer upon which a wheel will be received during a rerailing operation as will be described hereinafter.

The rerailer also includes an intermediate reinforcing cross wall or web 31, and from the outer upright wall 23 there are projected three flanges 32 shaped to rest as at 33 upon the base flange of the rail 5, and also to present lateral edges 34 for placement contact with the upright web of said rail 5. The inner upright wall 23 is equipped with a plurality of recesses 35 which extend down through the lower edge extremity of said wall, and the purposes of these recesses will be described hereinafter.

The rerailer top 26 is provided with an upstanding rerailer or camming rib 36 which includes a laterally flared receiving wall 37, well

rounded at its receiving end in the manner indicated at 38 in Figures 3 and 4.

The lower edge extremity of the inner upright wall 24 is shaped to provide a rest portion 39 for engaging upon the base flange of the curved closure rail 10.

The rerailer member 22 is illustrated in detail in Figures 9 through 13, and this member is formed to include an outer, laterally and downwardly sloping wall 40 and an inner upright wall 41 which converge toward a transverse, upright end closure wall 42. The upright walls 40 and 41 are connected by a top 43 which is horizontal and flat in cross section between the points 44 and 45. The top slopes down endwise slightly at 46 from the point 44 toward the end closure wall 42, and said top slopes in a more marked degree, as at 47, from the point 45 endwise toward the end extremity in which a wheel will be received during a rerailing procedure. The member 22 also includes an intermediate transverse reinforcing wall or web 48.

From the outer upright wall 39 there are projected a plurality of flanges 49 which are shaped to rest as at 50 upon the flange of the inside or curved stock rail 6, and said flanges terminate in lateral edges 51 which are disposed to engage in placing contact with the upright web of said rail 6. The inner upright wall 40 is equipped with a plurality of recesses 52 which extend downwardly through the lower edge thereof, and the purpose of these recesses will become apparent as this description progresses. The lower edge extremity of the inner upright wall 41 is shaped to provide a rest portion 53 for engaging upon the base flange of the rail 11.

The swing points or junctures 17 of the switch are provided by the plates 54 secured by bolts 55 to the webs of the switch points and to the points 7 and 8 with the closure rails 11 and 10 webs of the respective rails 10 and 11. Spacer means 56 may be employed to provide the desired freedom of movement of the switch points in the usual manner.

When the rerailer members 21 and 22 are properly mounted in the manner illustrated in Figures 1, 7 and 9 the respective upright wall recesses 35 and 52 straddle the nuts of the switch point attaching bolts 55 and this simple engagement of said recesses over the bolts serves as the sole means of holding the rerailer members against longitudinal displacement.

In the somewhat diagrammatic illustration in Figure 2 the rerailing of a pair of wheels is illustrated, the partially rerailed position of the wheels being shown in full lines and the fully rerailed condition being illustrated in dotted lines. It will be noted that the top 26 of the rerailer member 21 is disposed at a lesser height than the top 43 of the rerailer member 22, the difference in height being approximately the depth of a wheel flange. In other words when the flange of a wheel is resting upon the top 26 of the rerailer member 21, the main body of the wheel will be at an elevation for moving onto the adjacent rail 5. It will be apparent by reference to Figure 2 that the top 43 of the rerailer member 22 is at the same level as the top of the adjacent rail 11 so that the flange of a wheel being rerailed may readily pass over from said rerailer top onto said rail.

In order to rerail wheels which have jumped the switch and lie respectively between the converging rails 5—10 and 11—6, it is only necessary to draw the wheels toward the point of

convergence of said respective rail pairs, or in other words toward the rerailer members 21 and 22, and as said wheels contact the rerailer members they will ride up the somewhat flat and inclined slopes 30 and 41 of the rerailer members. As the wheels move over the flat tops of the rerailer members, one thereof comes against the rerailer or camming rib 36, 37 and is cammed laterally thereby to cause said wheels to move back onto the receiving rails in the manner indicated by dotted lines in Figure 2.

While one form of the invention has been shown for purposes of illustration it is to be clearly understood that various changes in the details of construction and arrangement of parts may be made without departing from the spirit and scope of the invention as defined in the appended claims.

I claim:

1. In a turnout, the combination with the outside straight stock rail, the inside curved stock rail, the straight and curved closure rails, the switch points, and the bolts forming a part of means swingably attaching said switch points to said closure rails, of a rerailer disposed opposite the juncture of each switch point and the connected closure rail and filling the converging space between the respective closure rail and the adjacent stock rail, each said rerailer having an upwardly inclined receiving end and a top onto which a wheel can be drawn from said end to ride over said top and be rerailed, and an upright wall opposing the respective switch point and closure rail juncture and equipped with recesses extending down through its lower edge and adapted to straddle and contact parts of the respective bolts as the sole means for retaining the rerailer against longitudinal movement.

2. Structure as defined in claim 1 in which each rerailer includes supporting portions disposed to rest upon base flanges of the adjacent rails, and also laterally extending edges for engaging rail web portions in a manner for preventing side play of the rerailer.

3. Structure as defined in claim 1 in which the top of each rerailer is flat and horizontal, and at least one said top includes an upstanding rib angularly disposed with relation to the adjacent rail onto which a wheel is to be rerailed so as to serve as a camming surface effective to force a wheel being drawn over said top laterally onto the adjacent rail.

4. Structure as defined in claim 1 in which the top of each rerailer is flat and horizontal, and at least one said top includes an upstanding rib angularly disposed with relation to the adjacent rail onto which a wheel is to be rerailed so as to serve as a camming surface effective to force a wheel being drawn over said top laterally onto the adjacent rail, each said rerailer also including supporting portions disposed to rest upon base flanges of the adjacent rails, and also laterally extending edges for engaging rail web portions in a manner for preventing side play of the rerailer.

5. Structure as defined in claim 1 in which the top of each rerailer is flat and horizontal, and the top of the rerailer adjacent the outside straight stock rail includes an upstanding rib angularly disposed with relation to the adjacent rail onto which a wheel is to be rerailed so as to serve as a camming surface effective to force a wheel being drawn over said top laterally onto the adjacent straight stock rail.

6. A rerailer placeable opposite the juncture of a switch point and the closure rail to which it

is attached and between said juncture and the adjacent converging stock rail in a railway turnout, said rerailer comprising a pair of upright web walls bearing converging relation to lie parallel adjacent rail webs, a flat horizontally disposed top at a height for effecting a rerailing of a wheel drawn thereover, and an upwardly inclined portion leading up to said top and being flat and horizontal in transverse section, said walls presenting bottom portions to rest upon rail base flanges, and at least one said wall having outwardly extending flange portions for resting on a rail base flange and terminating in outer edge portions for engaging with a rail web, one said wall having at least one recess therein and extending down through its lower edge and adapted to straddle a rail traversing bolt to constitute the sole means for holding the rerailer against longitudinal displacement and also permit mounting of the rerailer by merely dropping it into place after the switch on which it is used has been entirely set up.

7. A rerailer placeable opposite the juncture of a switch point and the closure rail to which it is attached and between said juncture and the adjacent converging stock rail in a railway turnout, said rerailer comprising a pair of upright web walls bearing converging relation to lie parallel adjacent rail webs, a flat horizontally disposed top at a height for effecting a rerailing of a wheel drawn thereover, and an upwardly inclined portion leading up to said top and being flat and horizontal in transverse section, and said top having an upstanding rib angularly disposed with relation to an adjacent stock rail onto which said rib is adapted to deflect a wheel so as to serve as a camming surface effective to force a wheel being drawn over said top laterally onto the adjacent stock rail, one said wall having at least one recess therein and extending down through its lower edge and adapted to straddle a rail traversing bolt to constitute the sole means for holding the rerailer against longitudinal displacement and also permit mounting of the rerailer by merely dropping it into place after the switch on which it is used has been entirely set up.

8. A rerailer placeable opposite the juncture of a switch point and the closure rail to which it is attached and between said juncture and the adjacent converging stock rail in a railway turnout, said rerailer comprising a pair of upright web walls bearing converging relation to lie parallel adjacent rail webs, a flat horizontally disposed top at a height for effecting a rerailing of a wheel drawn thereover, and an upwardly inclined portion leading up to said top and being flat and horizontal in transverse section, one said wall having at least one recess therein and extending down through its lower edge and adapted to straddle a rail traversing bolt to constitute the sole means for holding the rerailer against longitudinal displacement.

9. A rerailer placeable opposite the juncture of a switch point and the closure rail to which it is attached and between said juncture and the adjacent converging stock rail in a railway turnout, said rerailer comprising a pair of upright web walls bearing converging relation to lie parallel adjacent rail webs, a flat horizontally disposed top at a height for effecting a rerailing of a wheel drawn thereover, and an upwardly inclined portion leading up to said top and being flat and horizontal in transverse section, said walls presenting bottom portions to rest upon rail base flanges, one said wall having outwardly extending

flange portions for resting on a rail base flange and terminating in outer edge portions for engaging with a rail web, and the other said wall having at least one recess therein and extending down through its lower edge and adapted to straddle a rail traversing bolt to constitute the sole means for holding the rerailer against longitudinal displacement, and said top having an upwardly standing rib angularly disposed with relation to an adjacent stock rail onto which said rib is 10 adapted to deflect a wheel so as to serve as a camming surface effective to force a wheel being drawn over said top laterally onto the adjacent stock rail.

5
